INKING DEVICE FOR PRINTING-PRESSES.

1,194,004.

Specification of Letters Patent.

Patented Aug. 8, 1916.

Application filed January 29, 1915. Serial No. 5,163.

To all whom it may concern:

Be it known that we, DAVID W. FRACKELTON, RALPH S. TYLER, and WILLIAM M. REICHART, citizens of the United States, and residents of Cleveland, county of Cuyahoga, and State of Ohio, Cleveland Heights, county of Cuyahoga, and State of Ohio, and Cleveland, county of Cuyahoga, and State of Ohio, respectively, have jointly invented a new and useful Improvement in Inking Devices for Printing-Presses, of which the following is a specification, the principle of the invention being herein explained and the best mode in which we have contemplated applying that principle, so as to distinguish it from other inventions.

In platen printing presses, one approved method of inking the form consists in passing thereover a pair of inking rollers which are made of a special, more or less resilient, composition, such rollers being mounted in a reciprocating carriage and receiving the ink from a suitable fountain or like device disposed at the upper limit of such carriage's travel. In order, however, that the ink may be uniformly applied to the form, it is of course necessary that the ink thus received on these composition rollers be evenly distributed across the same, and it is furthermore necessary that such distribution or spreading of the ink on the rollers be continued during the period that they pass across the form, since otherwise the bare spaces left on the roller's contact with the first few lines of the form will fail to properly ink the succeeding lines. Accordingly, a secondary roller is frequently provided in connection with the inking rollers proper, the function of which is to spread the ink on the latter, not only during the first part of their travel but during their passage across the form, and in order that a thorough distribution may be effected this roller not only rotates but is also given a vibratory movement, that is a movement longitudinally of its axis.

The object of the present invention is to provide more especially an improved vibratory roller, with means for operating the

same, so that the device as a whole may be readily applied to present machines if desired.

A further object is to provide a device of simple construction and easy operation, so as to be unlikely to get out of order or to require much power.

To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing: Figure 1 is a side elevational view of our improved device as applied to a typical platen press; Fig. 2 is a broken plan view of such device; Fig. 3 is a transverse section taken on the line 3—3, Fig. 2; Fig. 4 is an end elevation of the device as viewed from the left in Fig. 2; Fig. 5 is a transverse section of a detail taken on the plane indicated by the line 5—5, Fig. 1; and Fig. 6 is a transverse section of another detail taken on the plane indicated by the line 6—6 Fig. 2.

Of the printing press proper only the bed 1 is illustrated, that is the part which holds the form. This part also supports the disk 2 over which the inking device passes in its travel from the fountain to such form. Such device comprises principally a series of composition rollers 3, 4 and 5 of familiar construction, which are supported at their respective ends by arms 6 and 7 movably mounted in oscillatory frames, springs (not shown) being usually provided in connection with said arms to retain such rollers in more or less close contact with the surface across which they travel. The forward roller 3 has the ends of its spindle 8 directly journaled in arms 6, while the two following rollers, 4 and 5, which are of more particular interest in the present connection, have the ends of their spindles 9 and 10

journaled in a saddle 11 that is pivotally attached to the outer ends of the corresponding arms 7. Oscillatory supported on the top of each of these saddles is a journal box 12 adapted to receive the corresponding end of the supporting shaft 13 of a third roller 14, which is ordinarily designated a vibratory roller because of the endwise reciprocable movement which it is desirably given. This roller is usually of metal and rests upon the two composition rollers 4 and 5, the degree of pressure being regulated by means of nuts 15 on threaded studs 16, one of which latter passes through a slot 17 in each of the journal boxes 12, as shown in Figs. 2 and 4. Said roller 14 is keyed at its one end to a sleeve that forms the hub of a pulley 18, rotatably mounted on said shaft but held against endwise movement therealong. As a result of the foregoing construction it will be seen that rotation of the pulley will rotate the roller, while still leaving the latter free to be reciprocated longitudinally of its axis.

In addition to the pulley 18 mounted as just described on shaft 13, two idler pulleys 19 are rotatably mounted on the spindles 9 and 10 of the composition rollers below. Passing between such two idler pulleys and looped over the pulley on the shaft 13 is a cord or round belt 20, the respective ends of which are fixedly attached to the machine bed 1 at points beyond the extreme limit of travel of the device downwardly across the bed and upwardly across the disk 2. One such point of attachment is preferably rendered adjustable by providing a take-up as shown in Fig. 1, such take-up consisting simply of a threaded metal clip 21 on the belt which passes through an upstanding ear or apertured lug 22, and has a nut 23 threaded on its outer end. By means of the foregoing the belt can be maintained under any desired degree of tension; the tension of such belt, however, will not be varied under normal operating conditions since it is supported in substantial parallelism throughout its length with the path of travel of the rollers 4 and 5 by means of grooved blocks 24 and 25 affixed to the bed or the frame, at each point where the direction of such travel changes.

From the foregoing construction it will be obvious that as the rollers are moved either across the disk 2 or the bed 1 of the press, the belt 20 passing between the idler pulleys 19 and around the driving pulley 18 on the spindle of the vibratory roller, will impart a positive rotative movement to the latter, the direction of rotation depending upon the direction in which the device as a whole is traveling, whether up or down. Obviously it is a matter of indifference just what form the belt may take, and this term

is to be hence understood as connoting, not simply the round belt, shown for illustrative purposes, but a flat belt, chain, or equivalent device. The longitudinally reciprocatory movement of this roller is produced incidentally to its rotation, by providing at one end thereof, preferably the end removed from the pulley 18, a continuous, reverse thread 26, which is engaged by a finger 27 carried on an arm 28 so as to lie midway of the total travel of the roller during such reciprocatory movement, (see Figs. 2 and 6). By virtue of this engagement, the roller as it is rotated, is shifted longitudinally first in one direction and then in the other the finger or nut traversing the reverse thread. It obviously makes no difference in which direction the roller is thus rotated, the number of turns required to produce the full longitudinal movement of the roller of course depending upon the steepness or pitch of such thread 26, and may be varied to suit the requirements of the service.

The foregoing construction of inking device, comprising, in combination with the two composition rollers 4 and 5, a vibratory roller driven by a belt disposed alongside of the path of travel of the rollers, constitutes a very simple arrangement for securing the positive rotation of such vibratory roller. At the same time the longitudinal movement of the roller is secured automatically, incidentally to its rotation, by means of the reverse thread and swiveled nut, so that the belt in effect constitutes the sole operating means for imparting both of the desired movements to said roller. The belt, as well as the vibratory roller, may moreover be readily attached to existing platen presses, since the journal boxes that support the roller are mounted directly on top of the saddles in which are held the spindles of the composition rollers, while the means for securing the belt to the frame of the machine may be equally readily applied to the latter.

As is well known, in place of an actual disk, such as shown and described herein as constituting the primary ink-distributing device, a roller or drum of relatively large diameter mounted on a stationary axis, is frequently used. The term disk should accordingly be understood as referring to any suitable primary ink-distributing device.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:—

1. In a platen printing press, the combi-

- nation with the bed and angularly related inking disk; of an inking roller adapted to be moved across and in contact with said bed and disk; a distributing roller mounted 5 so as to rotate in contact with said inking roller as the latter is thus moved; a pulley connected with said distributing roller; and a belt relatively fixedly attached at its ends and intermediately supported so as to have 10 one portion lie parallel with the bed and another angularly related portion parallel with the disk, said belt passing over said pulley so as to positively drive the same and said distributing roller.
- 15 2. In a platen printing press, the combination with the bed and angularly related inking disk; of an inking roller adapted to be moved across and in contact with said bed and said disk; a distributing roller mounted so as to rotate in contact with said inking roller as the latter is thus moved; a pulley connected with said distributing roller; a belt relatively fixedly attached at its ends and intermediately supported so as to have 25 one portion lie parallel with the bed and another angularly related portion parallel with the disk, said belt passing over said pulley so as to positively drive the same and said distributing roller; and means for 30 adjusting the tension of said belt.
3. In a platen printing press, the combination with the bed and angularly related inking disk; of an inking roller adapted to be moved across and in contact with said bed and disk; a distributing roller mounted so as to rotate in contact with said inking roller as the latter is thus moved; a pulley connected with said distributing roller; a belt relatively fixedly attached at its ends 35 and intermediately supported so as to have one portion lie parallel with the bed and another angularly related portion parallel with the disk, said belt passing over said pulley so as to drive the same and said distributing roller; and means coöperating with the latter to reciprocate the same longitudinally of its axis as it is thus driven.
4. In a platen printing press, the combination with the bed and angularly related 40 inking disk; of an inking roller adapted to be moved across and in contact with said bed and disk; a distributing roller mounted so as to rotate in contact with said inking roller as the latter is thus moved; a pulley connected with said distributing roller; a belt relatively fixedly attached at its ends 45 and intermediately supported so as to have one portion lie parallel with the bed and another angularly related portion parallel with the disk, said belt passing over said pulley so as to drive the same and said distributing roller; and means coöperating with the latter to reciprocate the same longitudinally of its axis as it is thus driven.
5. In a platen press, the combination with the bed and inking disk; of an inking roller adapted to be moved across and in contact with said bed and disk; a distributing roller mounted so as to rotate in contact with said inking roller as the latter is thus moved; a pulley connected with said distributing roller; an idler pulley rotatable about the axis of said inking roller; and a belt supported so as to lie parallel with the path of travel of said rollers and passing under said idler pulley and over the pulley connected with said distributing roller, so as to positively drive the latter.
6. In a platen printing press, the combination with the bed and inking disk; of two inking rollers adapted to be moved across and in contact with said bed and disk; a distributing roller mounted so as to rotate in contact with both of said inking rollers, as the latter are thus moved; a pulley connected with said distributing roller; two idler pulleys rotatable about the axes of said inking rollers; and a belt supported so as to lie parallel with the path of travel of said rollers and passing around said idler pulleys and over the pulley connected with said distributing roller, so as to positively drive the latter.
7. In a platen printing press, the combination with the bed and inking disk; of two inking rollers adapted to be moved across and in contact with said bed and disk; a distributing roller mounted so as to rotate in contact with both of said inking rollers, as the latter are thus moved; a pulley connected with said distributing roller; two idler pulleys rotatable about the axes of said inking rollers; a belt supported so as to lie parallel with the path of travel of said rollers and passing around said idler pulleys and over the pulley connected with said distributing roller, so as to positively drive the latter; and means coöperating with said distributing roller to reciprocate the same longitudinally of its axis as it is thus driven.
8. In a platen printing press, the combination with the bed and inking disk; of two inking rollers adapted to be moved across and in contact with said bed and disk; a distributing roller mounted so as to rotate in contact with both of said inking rollers, as the latter are thus moved; a pulley connected with said distributing roller; two idler pulleys rotatable about the axes of said inking rollers; a belt supported so as to lie parallel with the path of travel of said rollers and with said distributing roller, so as to positively drive the latter.

2
as to positively drive the latter; and means
coöperating with said distributing roller to
reciprocate the same longitudinally of its
axis as it is thus driven, said means including
5 an endless, reverse screw-thread on said
roller and a relatively stationary member
engaging such thread.

Signed by us, this 26 day of January, 1915.
